(57) **CLAIM**

The ornamental design for an LED lamp of street light, as
shown and described.

DESCRIPTION

FIG. 1 is a bottom perspective view of an LED lamp of street
light showing my new design;

FIG. 2 is a front view of FIG. 1;

FIG. 3 is a rear view of FIG. 1;

FIG. 4 is a left view of FIG. 1;

FIG. 5 is a right view of FIG. 1;

FIG. 6 is a top view of FIG. 1;

FIG. 7 is a bottom view of FIG. 1; and,

FIG. 8 is a top perspective view of FIG. 1.

The broken lines illustrate portions of the LED lamp of street
light, which form no part of the claimed design.
